J. A. WHERRY

COLLATED WORKSHEET

Filed June 14, 1922

Fig. I.

Inventor.

John A. Wherry
Chas. O'Neill
ATTORNEY

UNITED STATES PATENT OFFICE.

JOHN ASHLAND WHERRY, OF NEW ORLEANS, LOUISIANA.

COLLATED WORKSHEETS.

Application filed June 14, 1922. Serial No. 568,191.

To all whom it may concern:

Be it known that I, JOHN A. WHERRY, a citizen of the United States, residing at 5911 Prytania Street, in the city of New Orleans, State of Louisiana, have invented certain new and useful Improvements in Collated Worksheets; and I do hereby declare the following to be a full, clear, and exact description of the invention, such as

10 will enable others skilled in the art to which it appertains to make and use the same.

The invention relates to collated work sheets of the same general type as those disclosed in my co-pending application, Serial 15 No. 486,363, filed July 21st, 1921, Patent No. 1,424,967, associated with simple and effective means for locking the sheets together which will admit of the sheets being readily assembled in any desired relative adjustment

20 and as readily dis-associated or separated. To this end the invention comprises a main work sheet having a notch in its top edge and notches in its side edges near the top, a supplementary work sheet, which may be

25 associated with a subjacent transfer or carbon sheet, adapted to be folded over longitudinally and engaged at the fold with the top edge of the main sheet within the notch, and a continuous band or envelope adapted to be slipped over the associate sheets and engaged within the notches in the lateral edges of the main sheet, and thereby secure the assembled or collated sheets together.

30 The invention is illustrated in the accompanying drawings in which—

35 Fig. 1 is a front view of the preferred form of the invention involving collated main and supplementary sheets with an interposed transfer sheet and a locking band or envelope, the latter being broken away in part.

40 Fig. 2 is a section on line 2—2 of Fig. 1.

45 Referring to the drawings, 1 indicates the main sheet which may be in the form of a card, or leaf, for receiving the data and, for the purpose of illustration, is in the form of a ledger sheet having the usual heading space and column headings, and if desired, the customary column rulings commonly employed in sheets of this character. Near the top of the sheet 1 each of the side edges is provided with a notch 2 and preferably the upper edge is provided with an elongated notch 3. The supplementary

sheet 8, which in the form shown is an ordinary statement, is adapted to over-lie a portion of the main sheet, and is of a width sufficient to lie snugly within the slot 3 when said supplementary sheet is folded over longitudinally so as to overlap both the front and back faces of the main sheet, as shown. Ordinarily the supplementary sheet will be associated with a transfer sheet 10 of carbon paper or the like, which may be of the same size as the supplementary sheet and folded therewith to engage the notch 3 in the top edge of the main sheet. It will be understood that the main and supplementary sheets may be provided with the column and line space indicia and, if desired, with the usual spacings, rulings and indicia as described in my copending application aforesaid, and that the supplementary sheet may be adjusted and applied to the same purpose and effect as the supplementary sheet in said application.

50 In order to lock the main and supplementary sheets securely together so that they may be handled in the ordinary operations of inscribing the data on the sheets by a typewriting machine and filing the collated sheets in their proper places, there is provided a locking device which, in its preferred form, comprises an envelope 4 having a closed top 7 and open bottom and its upper corners cut away as at 5—5 so that end folds 6 engage the notches 2 in the side edges of the main sheet 1, the envelope constituting a continuous band which snugly surrounds the upper portion of the collated sheets, and which may be readily removed from interlocking relation with the main sheet by bending the latter slightly to release the folds 6 from the notches 2 and permit the envelope to be slipped off of the

55 60 65 70 75 80 85 90 95 100 105

assembled sheets.

If desired, the envelope 4 may take the form of a continuous band of a width substantially equal to the length of the notches 2 and without the top closure 7. In either form of the continuous locking band or envelope it will be seen that the same is of sufficient length to snugly engage the main sheet at the notches 2—2 and overlie the front and back folded sections of the supplementary and transfer sheets, as illustrated in Fig. 2, so that the latter will be securely held in properly adjusted position with re-

spect to the main sheet and the assembled or collated sheets may be readily handled during the ordinary course of business without danger of displacing or deranging any 5 of the sheets.

As indicated, the locking envelope or band 4 is provided with a sight opening 9, preferably covered by a transparent sheet, through which the identifying data on the 10 subjacent sheet would appear.

From the foregoing description it will be apparent that the main and supplementary sheets may be so relatively adjusted that the data inscribed on the main sheet 15 may represent a continuous record while the data applied to the supplementary sheet may represent only a part of the complete data, as described in my co-pending application aforesaid, as for example the main 20 sheet, when employed as a ledger record, may be used until it is completely filled on both sides and the supplementary sheet may be employed as a statement covering any desired period and when the period is complete 25 the supplementary sheet may be removed and replaced by a new one. When the main sheet has been filled on one side it is necessary only to remove the locking envelope, or band, and shift the supplementary sheet and associated transfer sheet 30 to the opposite face of the main sheet and then reverse the envelope or band so that the sight opening therein will overlie the rear face of the main sheet.

35 What I claim is:

1. The combination of a main work sheet having a notch in its top edge and notches in its side edges near the top, a supplementary work sheet adapted to be folded 40 over longitudinally and engaged at the fold with the top edge of the main sheet within the notch therein, and a continuous removable band of paper or the like surrounding the upper portion of the main sheet and

engaging the notches in the side edges of 45 the main sheet to secure the sheets together.

2. The combination with a main work sheet having a notch in its top edge and notches in its side edges near the top, a supplementary work sheet, a subjacent 50 transfer sheet, said latter sheets being adapted to be folded over longitudinally and engaged at the fold with the top edge of the main sheet within the notch therein, and a continuous removable band of paper or the like 55 surrounding the upper portion of the main sheet and engaging the notches in the side edges of the main sheet to secure the sheets together.

3. The combination with a main work sheet having a notch in its top edge and notches in its side edges near the top, a supplementary work sheet adapted to be folded over longitudinally and engaged at the fold with a top edge of the main sheet 60 within the notches therein, and a continuous band or envelope having a closed top, cut away top corners and side folds adapted to be slipped over the assembled sheets with the side folds engaged within the notches 65 of the side edges of the main sheet to lock the sheets together. 70

4. The combination with a main work sheet having a notch in its top edge and notches in its side edges near the top, a supplementary work sheet adapted to be folded over longitudinally and engaged at the fold with the top edge of the main sheet within the notch therein, and a continuous removable band of paper or the like 75 surrounding the upper portion of the sheet and engaging the notches in the side edges of the main sheet to secure the sheets together, said band having a sight opening in the face thereof. 80

In testimony whereof I affix my signature.

JOHN ASHLAND WHERRY.
